Attorney

UNITED STATES PATENT OFFICE

ALFRED MOORHOUSE, OF DETROIT, MICHIGAN, ASSIGNOR TO PACKARD MOTOR CAR COMPANY, OF DETROIT, MICHIGAN, A CORPORATION OF MICHIGAN

PUMP FOR INTERNAL-COMBUSTION ENGINES

Application filed November 16, 1927. Serial No. 233,548.

This invention relates to internal combustion engines and more particularly to pump mechanism for supplying fuel thereto.

In motor vehicles employing internal combustion engines as a source of motive power, the fuel supply tank for the motor is frequently arranged at a point lower than the motor carburetor necessitating the employment of a means, preferably operated by the motor, for raising fuel from the supply tank to the carburetor. One of the best known means for this purpose is a vacuum tank assisted by a vacuum pump driven from the camshaft.

15 An object of the invention is to provide a vacuum pump operated from the camshaft of an internal combustion engine.

Another object of the invention is to provide a vacuum pump comprising but few parts of simple structure arranged in a compact and unique manner, so that the pump will occupy but little space.

Another object of the invention is to provide a vacuum pump in which a guide member for the piston rod is supported between the pump casing and the cylinder.

Another object of the invention is to provide a vacuum pump having a casing with means for mounting the same upon the crankcase of an internal combustion engine and to construct the casing in such a manner that it will provide a suitable housing for the operating means of the pump and a suitable support for the pump proper.

35 Another object of the invention is to provide a vacuum pump having a piston which is simple in construction, efficient in operation and which will not score the cylinder wall.

40 A still further object of my invention is to provide a vacuum pump which has the advantages of a positive action, highly efficient in operation, and yet of marked simplicity as a whole and in respect to each of its component parts so that its manufacture is economically facilitated both as regards parts and their assembly.

Other objects of the invention will appear 50 from the following description taken in con-

nection with the drawings, which form a part of this specification and in which:

Fig. 1 is a side elevation of an internal combustion engine and vacuum tank illustrating my improved pump mounted upon the engine and connected to the tank and the mixing tube of the engine carburetor,

55 Fig. 2 is a vertical sectional view of a portion of a crankcase with the pump mounted thereon, and

Fig. 3 is a vertical sectional view taken substantially on line 3—3 of Fig. 2.

Referring to the drawings for more specific details of the invention, 10 represents generally, an internal combustion engine including a crankcase 11 having mounted therein a camshaft 12. A cylinder block 13 is supported by the crankcase and provided with a manifold 14 from which is suspended a carburetor 15. The carburetor receives its fuel supply through a pipe line 16 leading from a vacuum tank 17 suitably supported in a position adjacent to and above the engine and the vacuum tank receives its supply through a pipe line 18 leading from the main supply tank, not shown. The vacuum tank may be of any well known type, now in general use on motor vehicles, for raising gasoline from the main supply tank to a level above the motor carburetor, so that gasoline may be fed by gravity from the vacuum tank to the carburetor.

70 One end of the crankcase is apertured as indicated at 19 in axial alignment with the camshaft 12 and mounted in the aperture is a casing 20. As shown, the casing 20 comprises a disk 21, the periphery of which is shouldered as indicated at 22 to fit snugly in the aperture. This disk is secured in position by rivets 23 or suitable means and has formed integral therewith a central sleeve portion 24 terminating in a bend or elbow 25 flanged as indicated at 26 and shouldered as at 27 to provide a suitable support for a guide member 28 and a cylinder 29 to be herein- 75 after described.

90 The guide member 28 has a substantially cylindrical body portion apertured as at 30 to provide suitable lubricating passages and is provided at one end with a radial flange 31 95

adapted to bear upon the flange 26 and a depending lip or flange 31' adapted to engage the shoulder 27, the flange 31 being shouldered as indicated at 32, the object of which will hereinafter appear. The other 5 end of the guide member has an internal shoulder portion 33 supporting a depending integral sleeve 34 positioned axially within the body portion and extending substantially therethrough, the upper end of the sleeve 10 being flared as indicated at 35 to provide a lubricant reservoir.

The cylinder 29 has a flange 36 bearing upon the shoulder 32 of the guide member 28 and secured by suitable means, not shown, to the flange 26 of the casing 20 with the radial flange 31 on the guide member 28 interposed. The cylinder 29 is closed at the top as indicated at 37 and provided with an interior circumferential groove 38. On the top of the cylinder is a boss 39, bored and threaded to receive a plug 40, the bore communicating with the cylinder by means of a port 41. The plug 40 has an axial bore 42 and an enlarged axial counter bore 43 in which is mounted a ball 44 adapted to close the port 41. Connected to the plug 40 by a suitable connection 45 is a pipe line 46, leading to the mixing chamber of the carburetor 15.

Formed upon the wall of the cylinder 29 at the upper end thereof is a boss 47 having a bore 48 threaded to receive a nipple 49 and a bore 50 normal to the bore 48 and communicating therewith by means of a port 51. The bore 50 is threaded to receive plug 52 and has a port 53 communicating with the circumferential groove 38 in the top of the cylinder. The plug 52 is recessed to receive a ball 54 adapted to close the port 53 and the nipple 49 is connected by means of a suitable connection 55 to a pipe line 56 leading to the top of the vacuum tank 17.

As shown, the forward end of the camshaft is threaded to receive an extension member 57 secured in a fixed position by a pin 58. This extension member projects into the casing 20 and is provided upon its free end with a cam 59. Mounted in the cylinder 29 is a piston 60 having a head 61 and a skirt portion 62, the bottom edge of which is curved inwardly as indicated at 63 to provide a strengthening rib and to provide means preventing scoring of the cylinder wall.

Connected to the head portion of the piston by a plate 64 is a piston rod 65 having a head 66 seated in a depression 67 in the plate 64 and bearing upon the piston head. The piston rod 65 is mounted to reciprocate in the sleeve 34 and has upon its lower end 68 a thimble 68 having a radial flange 69 which provides an abutment for one end of a coiled spring 70 mounted upon the sleeve 34 with its other end bearing against the shoulder 33. The spring 70 serves to normally hold the 63 thimble 68 in engagement with the extension

member 57 for cooperation with the cam shaft 59 whereby the piston is actuated to reciprocate in the cylinder.

Upon reciprocation of the piston within the cylinder, the ports 41 and 51 are successively opened and closed to pump air from the vacuum tank 17 through the pipe line 56 to and through the pump, thence through the pipe line 46 to the mixing chamber of the carburetor, thereby assisting in the creation of a vacuum in the vacuum tank to raise the fuel from the supply tank to the vacuum tank from which it is fed by gravity to the carburetor and at the same time modifying the mixture in the mixing chamber according to the speed of the engine.

It is to be understood that the form of the invention herein shown and described is to be taken as the preferred example of the same and that various changes in shape, size and arrangement of parts may be resorted to without departing from the spirit of the invention or the scope of the subjoined claims.

Having thus described the various features of my invention what I claim as new and desire to procure by Letters Patent is:

1. In a pump mechanism, the combination of a two part casing, a guide member interlocking said parts, the guide portion of said member extending in spaced telescopic relation with one part of the casing, a piston rod mounted in said guide member and a piston in the casing part telescoping the guide carried by said rod.

2. In a pump mechanism, the combination of a casing, a guide member telescoping the casing, a cylinder telescoping the guide member, a piston rod mounted in the guide member and a piston in the cylinder telescoping the guide member.

3. In a pump mechanism, the combination of a casing having a supporting flange and an opening, a guide member positioned over the opening having a part fitted therewithin a cylinder over the guide member, means for securing the cylinder and casing together with the guide member secured between a piston rod mounted to reciprocate in the guide member and a piston carried by the rod and telescoping a portion of the guide member in the cylinder.

4. In a pump mechanism the combination with a casing, of a piston structure comprising a head and a skirt portion, a reinforcing plate secured to the head portion of the piston for rotatably attaching a piston rod.

5. In a pump mechanism, the combination with a casing, of a piston comprising a head and a skirt portion, an inturned flange on the bottom of the skirt portion, a reinforcing plate on the head portion, said reinforcing plate having a depression with an aperture therein, a piston rod extending through the aperture in the plate and a head on the rod fitting into the depression in the plate.

6. A pump element comprising a guide member having a radial supporting flange and an inturned shoulder portion and a sleeve depending from the shoulder portion and flared at its upper end to provide an oil reservoir.

7. A pump element comprising a guide member having a supporting flange and an interior sleeve, the walls of the guide member being slotted to provide lubricating passages.

8. A pump element comprising a guide member having on one end thereof a radial flange and a depending lip for supporting the guide member, an inturned shoulder on the other end of the guide member and an internal sleeve depending from said shoulder.

9. A pump element comprising a guide member having formed upon one end thereof a radial flange and a depending lip for supporting said member, an inturned shoulder on the other end of the guide member having a depression therein, a sleeve formed integral with the shoulder and depending therefrom and communicating with the depression.

10. A pump element comprising a guide member having on one end thereof a shoulder flange and a depending lip adapted to support the guide member, the other end of the guide member having an inturned shoulder with a sleeve integral therewith, said sleeve being positioned axially within the guide member, said guide member having lubricating passages in its wall and a lubricant collecting chamber in the top thereof.

11. In a pump mechanism, a casing having a supporting flange and an opening, a guide member in said opening, said guide member having a substantially cylindrical wall and a depending internal sleeve, a cylinder mounted over said opening clamping said guide member on said casing, a piston rod mounted to reciprocate in the sleeve, a piston upon one end of the piston rod, a thimble upon the other end of the rod and a spring upon the sleeve abutting said thimble.

12. In a pump mechanism, a casing having a supporting flange and an opening, a guide member mounted on said casing over the opening, a flange on the guide member engaging the opening, said guide member having a hollow body portion supporting an internal sleeve, a cylinder mounted upon the guide member and secured to the casing, a piston rod mounted in the sleeve, a piston on one end of the rod, a thimble on the other end of the rod, and a spring on the sleeve bearing upon said thimble.

13. In a pump mechanism, a casing having a supporting flange and an opening, a guide member having a slip joint connection with the casing, a defending internal sleeve in the guide member, a piston rod mounted to re-

ciprocate in the sleeve, a piston on one end of the piston rod, a thimble on the other end of the piston rod and a spring on the sleeve abutting the thimble.

14. A pump mechanism comprising a casing, a telescopically formed guide member having an interlocking connection with the casing, a cylinder supported by the guide member having an interlocking connection therewith means for securing the cylinder to the casing with the guide member interposed, inlet and exhaust valves in the top of the cylinder, a piston rod mounted in the guide member, a piston on one end of the rod and a thimble on the other end of the rod and a coil spring extending intermediate the guide member walls and pressing against the thimble.

15. In a pump mechanism, a casing having an opening therein, a guide member mounted in said opening, an inturned shoulder on the guide member, an internal sleeve supported by the shoulder, the guide member having lubricating slots in its side walls and a lubricating reservoir in the top thereof, a cylinder enclosing the guide member having intake and outlet ports, a piston rod mounted to reciprocate in the sleeve, a piston on one end of the rod, a thimble on the other end of the rod, a spring wound upon the sleeve with its respective ends abutting the inturned shoulder and the thimble on the piston rod and a cam coacting with the thimble for actuating the piston.

16. In an engine having a crankcase and cam shaft, a pump mechanism comprising a sectional casing secured to and in open communication with the crankcase, a guide member intermediate the casing sections, a piston in the casing section remote from the crankcase, and a piston rod projecting through the guide member and actuated by the cam shaft, said guide member having apertures therein to allow passage of lubricant therethrough.

In testimony whereof I affix my signature.
ALFRED MOORHOUSE.
